Patented Nov. 12, 1968

212,678

COMPARTMENTED CARRYING CONTAINER AND THE LIKE

James Baldwin Swett, 8 Devonshire Drive,
Barrington, R.I. 02806

Filed July 27, 1967, Ser. No. 8,019

Term of patent 14 years

(Cl. D9—185)

FIG. 1

FIG. 2

FIG. 3

FIG. 4

FIG. 5

FIG. 6

FIG. 8

FIG. 9

FIG. 10

FIG. 7

FIGURE 1 is a perspective view of a compartmented carrying container and the like showing my new design; FIG. 2 is a top plan view; FIG. 3 is a bottom plan view; FIG. 4 is a side elevational view; FIG. 5 is a right end elevational view; FIG. 6 is a left end elevational view; FIG. 7 is a perspective view of the lower member; FIG. 8 is a top plan view thereof; FIG. 9 is a bottom plan view of the cover member; and FIG. 10 is an enlarged sectional view taken on line 10—10 of FIGURE 2 with portions thereof enlarged for convenience of illustration.

The essential features of my design are shown in full lines on the drawings.

I claim:

The ornamental design for a compartmented carrying container and the like, substantially as shown and described.
